UNITED STATES PATENT OFFICE

2,253,185

ELECTRIC DISCHARGE APPARATUS

Harold W. Lord, Schenectady, N. Y., assignor to
General Electric Company, a corporation of
New York

Application August 31, 1940, Serial No. 355,045

6 Claims. (Cl. 176—124)

My invention relates to apparatus for effecting the starting of an electric discharge device, such as an electric discharge lamp, which is arranged to be operated from a constant current supply circuit and is provided with electrodes one or more of which are adapted to be heated before the discharge in the device is started. One object of my invention is to provide improved apparatus of this character by which the application of the starting voltage is delayed until the temperature of the heated electrode or electrodes has reached the desired point. Another object of my invention is the provision in such apparatus of means for producing a more rapid electrode heating.

My invention will be better understood from the following description taken in connection with the accompanying drawing, and its scope will be pointed out in the appended claims.

In the single figure of the drawing which is a circuit diagram illustrating one embodiment of my invention, 1 is an electron discharge device such for example as a sodium lamp shown having the spaced filamentary electrodes 2 and 3 which when the device is operated from an alternating current circuit alternately function as cathodes. The electrodes 2 and 3 are connected at one end respectively through the leads 4 and 5 with the constant current supply circuit 6 which is shown including the usual film cut-out 7 arranged between the connecting leads.

Associated with the device 1 is the transformer 10, on the core 11 of which are the four windings 12, 13, 14, and 15. Winding 13 connects through the contacts of the relay 16 with the opposite ends of the electrodes 2 and 3, thereby constituting a short circuit across the device 1, the current of the circuit 6 being passed through the electrodes during the initial heating period. At this time the winding 13 functions as the primary of the transformer, the windings 12 and 14 functioning as secondary windings which by connecting across the electrodes 2 and 3 respectively supply supplemental heating current to those electrodes. If, for example, the current of the constant current circuit is 6.6 amperes the total current flowing through the electrodes during the heating period when supplemented by the windings 12 and 14, may be 8.6 amperes.

It will be noted that inasmuch as the apparatus is supplied from a constant current source the increase in the resistance across each of the electrodes, due to the rise in temperature thereof, will result in a greater potential difference across each electrode and hence a greater po-

tential difference between the leads 4 and 5. The winding of the relay 16 is connected in series with the capacitor 17 and the secondary winding 15, the voltage of which supplements the voltage across the leads. During the heating interval this combined voltage of the winding 15 and that across the leads is insufficient to operate the relay; however, when the electrodes have reached their desired electron emitting temperature the voltage across the leads 4 and 5 will have increased to such a value that it, together with the augmented voltage of the winding 15 due to the higher voltage across the leads, will cause the operation of the relay, thus opening the shunt circuit including the winding 13. By so doing, the voltage of the supply circuit is applied across the device which starts the discharge therein.

During the normal operation of the device the windings 12 and 14 carry a small current by reason of the voltage drop through the electrodes and at this time these windings function as the primary of the transformer. The voltage then induced in the winding 15, taken together with the voltage between the leads 4 and 5, is sufficient to maintain the relay in open circuit position. The capacitor 17 is constructed to offer a minimum amount of impedance, the purpose of the capacitor being to prevent any direct current due to lamp rectification from flowing through the relay and transformer windings.

I have shown the particular embodiment described above as illustrative of my invention and it will be apparent that various modifications may be made without departing from the spirit and scope of my invention which modifications I aim to cover by the appended claims.

What I claim as new and desire to secure by Letters Patent of the United States, is:

- 40 1. In combination, an electric discharge device having spaced electrodes arranged to be connected in a constant current alternating supply circuit, means for producing an initial heating of one of said electrodes comprising means for passing said current therethrough and a transformer having its primary connected to be energized by said current and its secondary connected to supplement said current in said electrode.
- 45 2. In combination, an electric discharge device having spaced electrodes arranged to be connected in a constant current alternating supply circuit, means for producing an initial heating of said electrodes comprising means for passing said current through said electrodes and a

transformer having its primary connected between said electrodes and having a plurality of secondary windings each connected across one of said electrodes to supply a supplemental current thereto.

3. In combination, an electric discharge lamp having filamentary electrodes, means for connecting said lamp in a constant current circuit, means for passing the current of said circuit in series through said electrodes to initially heat them, and means responsive to the increase in voltage applied to said lamp due to the heating of said electrodes and the properties of said circuit for opening the circuit between the electrodes.

4. In combination, an electric discharge lamp having filamentary electrodes adapted to be initially heated by the passage of current therethrough, means connected with one end of each of said electrodes for including said lamp in a constant current circuit, a switch connected between the opposite ends of said electrodes and means responsive to the increase in voltage between the first mentioned ends of said electrodes as the electrodes become heated for opening said switch.

5. In combination, an electric discharge lamp having filamentary electrodes adapted to be ini-

20 tially heated by the passage of current therethrough, means connected with one end of each of said electrodes for including said lamp in a constant current circuit, a transformer having a primary and a secondary, a switch, means connecting said primary and said switch in series between the opposite ends of said electrodes, opening means for said switch, and means connecting said opening means and said secondary in series between the first mentioned ends of said electrodes.

6. In combination, an electric discharge lamp having filamentary electrodes adapted to be initially heated by the passage of current therethrough, means connected with one end of each of said electrodes for including said lamp in a constant current circuit, a transformer having a primary and a plurality of secondaries, means connecting a secondary across each of said electrodes, a switch connected in series with said primary between the other ends of said electrodes, an opening magnet for said switch and means connecting said magnet and another secondary in series between the first mentioned ends of said electrodes.

HAROLD W. LORD.
